CONTROL FOR AIR CONDITIONING
SYSTEMSCharles D. Graham, Dayton, Ohio, assignor to
General Motors Corporation, Dayton, Ohio, a
corporation of Delaware

Application November 20, 1943, Serial No. 511,079

15 Claims. (Cl. 62-3)

1

This invention relates to refrigerating apparatus and more particularly to an improved arrangement for controlling the flow of refrigerant in a fixed restrictor type of refrigeration system.

One object of this invention is to improve the humidity control in an air conditioning system using a fixed restrictor type of refrigerant flow regulator.

Another object of this invention is to utilize the hot refrigerant gas for vaporizing a portion 10 of the liquid refrigerant flowing through the fixed restrictor.

Still another object of this invention is to provide means for by-passing a portion of the refrigerant from the high side of the compressor to the 15 low side of the compressor in a fixed restrictor system.

A further object of this invention is to provide an improved air conditioning system in which the flow of refrigerant to the evaporator is throttled at light sensible cooling loads and in which the ratio of latent cooling to sensible cooling is increased upon a decrease in the demand for sensible cooling.

Further objects and advantages of the present invention will be apparent from the following description, reference being had to the accompanying drawings, wherein a preferred form of the present invention is clearly shown.

In the drawings:

Fig. 1 diagrammatically shows an air conditioning system incorporating my improved control; and

Fig. 2 is a diagrammatic view showing a modification of the air conditioning system shown in Fig. 1.

Referring now to the drawings, the air to be conditioned is passed through an air conditioning chamber 10 by means of a fan 11, which may be driven in any suitable manner as by the electric motor 12. This air is then passed to the space 16, to be conditioned 16, through the air outlet 14. A fresh air inlet 18 and a return air inlet 20 are provided in accordance with standard practice. Dampers 22 and 24 may be used for controlling the proportions of fresh and return air admitted to the chamber 10. These dampers may be manually operated or automatically operated in any suitable manner. Thus temperature or humidity responsive means, or a combination of both, may be used for controlling either one or both of these dampers, in accordance with either the condition of the inside air, the outside air or a combination of both.

An evaporator 26 is provided in the chamber 55

10 directly in the path of the air to be conditioned. Reference numeral 28 designates a conventional motor-compressor unit which is used in compressing the refrigerant and discharging a compressed refrigerant into the line 30 which leads to the condenser 32. The refrigerant condensed in the condenser 32 collects in the receiver 34 and is conveyed to the evaporator through the refrigerant line 36, in which there is mounted a fixed restrictor 38. The fixed restrictor 38 is preferably of the well known type which includes a relatively long, narrow capillary passage which serves to reduce the pressure of the refrigerant as it flows through the restricted passage into the evaporator 26, which is maintained under suction by operation of the motor-compressor unit 28. Reference numeral 40 designates the suction line leading from the evaporator to the motor-compressor unit 28.

20 It has been found that frequent cycling of the motor-compressor unit is objectionable in an air conditioning system since the change in the temperature and the humidity of the air discharged from the chamber 10 upon cycling is very noticeable in the conditioned space.

I have found that the flow of refrigerant through a fixed restrictor may be varied by the application of heat to the liquid refrigerant flowing from the receiver to the fixed restrictor. By 30 adding heat to the liquid refrigerant so as to partially vaporize the refrigerant passing through the fixed restrictor the amount of refrigerant which passes through the fixed restrictor is reduced.

35 In order to heat the liquid refrigerant flowing from the receiver 34 to the restrictor 38, I have provided a hot refrigerant gas by-pass line 42 in which there is provided a heat interchanger 44 and a second fixed restrictor 46. A valve 48 controls the flow of refrigerant through the by-pass 42. The valve 48 is controlled by means of a thermostat 50 located in the path of the air leaving the evaporator 26. The heat interchanger 44 is of standard construction and includes one 45 pass through which the hot compressed gas flowing through line 42 passes, and a second pass through which the liquid refrigerant in the line 36 flows. The heat interchanger could surround the restrictor 38, if desired.

50 By virtue of the above described arrangement the flow of refrigerant to the evaporator may be controlled without reducing the suction pressure an excessive amount, since the hot gas flowing through the by-pass 42 in which the heat interchanger 44 is located is added to the gas return-

ing from the evaporator to the motor-compressor unit 28. A restrictor 46 is provided in the by-pass line 42 and serves to reduce the pressure of the gas flowing through the by-pass 42 so as to relieve the valve 48 from taking the entire pressure drop. This restrictor may be omitted if desired.

The valve 48 is preferably a modulating valve, although an on and off valve could be used but would not give the gradual control which a modulating valve would obviously give.

For purposes of illustration I have shown a room thermostat 52 for controlling the motor-compressor switch 54. The thermostat 52 operates the switch 54 through the bellows 56 in accordance with well known practice. Electrical energy is supplied to the motor-compressor unit 28 through the power lines designated by the reference numeral 58.

In Fig. 2 of the drawing I have shown a somewhat similar arrangement, including an air conditioning chamber 110 through which the air to be conditioned is circulated by means of a fan 111 driven by a motor 112. The conditioned air is discharged through the outlet 114 into the conditioned space 116. A fresh air inlet 118 and a return air inlet 120 are provided for supplying air to the conditioning chamber 110 in accordance with well known practice. Dampers 122 and 124 are provided for controlling the proportions of fresh air and return air entering the conditioning chamber 110. These dampers may be controlled by means of any suitable temperature or humidity controls (as explained in connection with dampers 18 and 20 of Fig. 1). The air to be conditioned is cooled by means of the evaporator sections 125 and 126 which are arranged in parallel refrigerant flow relationship. A pair of restrictors 138 and 139 are provided as shown for controlling the flow of refrigerant to the evaporator sections 126 and 125 respectively. The restrictors 138 and 139 are preferably of the type including a relatively long, narrow capillary passage through which the liquid is required to pass on its way to the evaporator. A motor-compressor unit 128 is provided for withdrawing the refrigerant vapor from the evaporator sections 125 and 126 in accordance with standard practice. A valve 129 is placed in the suction line and is of the type which prevents the pressure within the evaporator sections 125 and 126 from becoming low enough to freeze the condensate on the evaporator sections 125 and 126. The valve 129 includes the usual pressure line 131. The compressed refrigerant is discharged into the condenser 132 wherein it is condensed before entering the receiver 134. A valve 148 is provided in the line 142 leading to the evaporator section 125. A valve 148 is controlled by means of a thermostat 150 located in the path of the air leaving the evaporator sections 125 and 126. It will be noted that the thermostat 150 is placed at the outlet of the fan, whereby the air flowing thereover is a thorough mixture of the air flowing over the two evaporator sections 125 and 126.

For purposes of illustration I have shown a thermostat 152 for controlling the mercury contact switch 154, arranged in the power line 158, which supplies electrical energy to the motor-compressor unit 128. The usual form of bellows 166 is connected to the thermostatic bulb 152 as shown, for operating the switch 154.

The thermostat 152 is preferably adjusted so as to turn off the motor-compressor unit 128 whenever the temperature within the conditioned space falls below a predetermined value. Under

normal conditions the thermostat 152 will seldom turn off the motor-compressor unit as the amount of cooling will largely be controlled by the thermostat 150 which operates the valve 148. As the temperature of the air supplied to the conditioned space 116 falls below a predetermined value, indicating that the air conditioning system has more capacity than required for reducing the dry bulb temperature in the conditioned space, the valve 148 will begin to close and throttle the flow of refrigerant to the evaporator section 125. As the flow of refrigerant to the evaporator section 125 is decreased, the total amount of cooling will be reduced. Closing of the valve 148, either partially or completely, will tend to reduce the suction pressure in the evaporator means. The reduction in the suction pressure will tend to reduce the temperature prevailing in the evaporator, but inasmuch as the total amount of effective evaporator surface will be reduced because of the reduction in the amount of refrigerant supplied to the evaporators, the total reduction in the dry bulb temperature will be less, but the effective evaporator surface will remove an increased amount of moisture as a result of the lower temperature.

While I prefer placing the thermostats 50 and 150 in the outgoing air stream, they could be located directly in the conditioned space or in the path of the air entering the evaporator. The location of the thermostat depends partly upon the type of air conditioning installation and the effect desired. Wet bulb thermostats or humidistats could be substituted for the dry bulb thermostats for some purposes.

While the form of embodiment of the invention as herein disclosed constitutes a preferred form, it is to be understood that other forms might be adopted, as may come within the scope of the claims which follow:

What is claimed is as follows:

1. In a refrigerating system, evaporator means, means for flowing air in thermal exchange relationship with said evaporator means, condenser means, refrigerant compressor means for withdrawing vaporized refrigerant from said evaporator means and for discharging compressed refrigerant into said condenser means, fixed restrictor means controlling the flow of refrigerant from said condenser means to said evaporator means, and means for by-passing refrigerant from a point ahead of said fixed restrictor to a point beyond said evaporator means in response to a decrease in the temperature of the air leaving said evaporator means.

2. In a refrigerating system, evaporator means, condenser means, refrigerant compressor means for withdrawing vaporized refrigerant from said evaporator means and for discharging compressed refrigerant into said condenser means, fixed restrictor means controlling the flow of refrigerant from said condenser means to said evaporator means, means for by-passing refrigerant from the inlet side of said fixed restrictor to the outlet side of said evaporator means, and a valve means controlling the flow of refrigerant through said by-passing means.

3. In a refrigerating system, evaporator means, condenser means, refrigerant compressor means for withdrawing vaporized refrigerant from said evaporator means and for discharging compressed refrigerant into said condenser means, fixed restrictor means controlling the flow of refrigerant from said condenser means to said evaporator means, means for by-passing re-

refrigerant from the inlet side of said fixed restrictor to the outlet side of said evaporator means, valve means controlling the flow of refrigerant through said by-passing means, and a fixed restrictor in said by-passing means.

4. In a refrigerating system, evaporator means, condenser means, refrigerant compressor means for withdrawing vaporized refrigerant from said evaporator means and for discharging compressed refrigerant into said condenser means, fixed restrictor means controlling the flow of refrigerant from said condenser means to said evaporator means, means for bypassing said evaporator with a portion of the refrigerant, a valve means controlling the flow of refrigerant through said by-passing means, and a fixed restrictor in said by-pass, said by-pass including a heat interchanger arranged in thermal exchange relationship with the refrigerant flowing to said first named restrictor.

5. In a refrigerating system, evaporator means, condenser means, refrigerant compressor means for withdrawing vaporized refrigerant from said evaporator means and for discharging compressed refrigerant into said condenser means, fixed restrictor means controlling the flow of refrigerant from said condenser means to said evaporator means, by-pass means for flowing compressed refrigerant vapor from the outlet of said compressor means to the inlet of said compressor means, said by-pass means including means for flowing the compressed refrigerant vapor in thermal exchange relationship with the refrigerant flowing to the evaporator.

6. In a refrigerating system, evaporator means, condenser means, refrigerant compressor means for withdrawing vaporized refrigerant from said evaporator means and for discharging compressed refrigerant into said condenser means, fixed restrictor means controlling the flow of refrigerant from said condenser means to said evaporator means, by-pass means for flowing compressed refrigerant vapor from the outlet of said compressor to the inlet of said compressor, said by-pass means including means for flowing compressed refrigerant vapor in thermal exchange relationship with the refrigerant flowing to the evaporator, said by-pass means including a fixed restrictor adjacent the outlet thereof.

7. In a refrigerating system, a first evaporator, a second evaporator, condenser means, compressor means for withdrawing vaporized refrigerant from said evaporators and for discharging compressed refrigerant into said condenser means, means for flowing refrigerant from said condenser means to said first and second evaporators in parallel, a first fixed restrictor controlling the flow of refrigerant to said first evaporator, a second fixed restrictor controlling the flow of refrigerant to said second evaporator, and valve means responsive to the temperature of the conditioned air for controlling the flow to one of said fixed restrictors.

8. In a refrigerating system, a first evaporator, a second evaporator, condensing means, means including a compressor for withdrawing vaporized refrigerant from said evaporators and for discharging compressed refrigerant into said condenser means, means for flowing refrigerant from said condenser to said first and second evaporators in parallel, a first fixed restrictor controlling the flow of refrigerant to said first evaporator, a second fixed restrictor controlling the flow of refrigerant to said second evaporator, valve means responsive to the temperature of

the conditioned air for controlling the flow of refrigerant to one of said fixed restrictors, and a pressure regulating valve adjacent the inlet of said compressor for limiting the suction pressure on said evaporators.

9. In a refrigerating system, a first evaporator, a second evaporator, condenser means, compressor means for withdrawing vaporized refrigerant from said evaporators and for discharging compressed refrigerant into said condenser means, means for flowing refrigerant from said condenser to said first and second evaporators in parallel, a first fixed restrictor controlling the flow of refrigerant to said first evaporator, a second fixed restrictor controlling the flow of refrigerant to said second evaporator, valve means responsive to the temperature of the conditioned air for controlling the flow of refrigerant to one of said fixed restrictors, a pressure regulating valve in the suction line leading to the compressor for limiting the suction pressure on said evaporators, and means responsive to the temperature of the conditioned air for starting and stopping the operation of said compressor.

10. In a refrigerating system, a first evaporator, a second evaporator, condenser means, compressor means for withdrawing vaporized refrigerant from said evaporators and for discharging compressed refrigerant into said condenser means, means for flowing refrigerant from said condenser to said first and second evaporators in parallel, a first fixed restrictor controlling the flow of refrigerant to said first evaporator, a second fixed restrictor controlling the flow of refrigerant to said second evaporator, means controlling the flow of refrigerant to one of said fixed restrictors, and a pressure regulating valve in the suction line leading to the compressor for limiting the suction pressure on said evaporators.

11. Air conditioning apparatus for an enclosure comprising in combination, means forming a conditioning chamber, means for flowing air through said chamber, evaporator means arranged in thermal exchange with the air flowing through said chamber, a condenser, a compressor for withdrawing refrigerant vapor from said evaporator means and for discharging compressed refrigerant into said condenser, a pair of fixed restrictors controlling the flow of refrigerant to said evaporator means, means for controlling the flow of refrigerant through one of said fixed restrictors and means for preventing the pressure within said evaporator from dropping below a pre-determined value.

12. Air conditioning apparatus for an enclosure comprising in combination, means forming an air conditioning chamber, blower means for blowing air through said chamber into said conditioned space, an evaporator in said chamber, condenser means, compressor means for withdrawing vaporized refrigerant from said evaporator and for discharging the compressed refrigerant into said condenser means, means for by-passing said evaporator with a portion of the compressed refrigerant, a fixed restrictor controlling the flow of refrigerant through said evaporator, and a fixed restrictor for controlling the flow of refrigerant through said means for by-passing the evaporator.

13. Air conditioning apparatus for an enclosure comprising in combination, means forming an air conditioning chamber, blower means for blowing air through said chamber and into said enclosure, an evaporator in said chamber, con-

denser means, compressor means for withdrawing vaporized refrigerant from said evaporator and for discharging the compressed refrigerant into said condenser, means for by-passing said evaporator with a portion of compressed refrigerant, a fixed restrictor controlling the flow of refrigerant through said evaporator, a fixed restrictor for controlling the flow of refrigerant through said means for by-passing a portion of the refrigerant, and means responsive to the temperature of the conditioned air for controlling the flow of refrigerant through one of said fixed restrictors.

14. Air conditioning apparatus for an enclosure comprising in combination, means forming an air conditioning chamber, blower means for blowing air through said chamber and into said enclosure, an evaporator in said chamber, condenser means, compressor means for withdrawing vaporized refrigerant from said evaporator and for discharging the compressed refrigerant into said condenser, means for by-passing said evaporator with a portion of compressed refrigerant, a fixed restrictor controlling the flow of refrigerant through said evaporator, a fixed restrictor for controlling the flow of refrigerant through said means for by-passing the evaporator, means responsive to the temperature of the conditioned air for controlling the flow of refrigerant through one of said fixed restrictors, and means responsive to the temperature of the

air within said enclosure for controlling the operation of said compressor.

15. In a refrigerating system, evaporator means, means for flowing air in thermal exchange relationship with said evaporator means, condenser means, refrigerant compressor means for withdrawing vaporized refrigerant from said evaporator means and for discharging compressed refrigerant into said condenser means, means controlling the flow of refrigerant from said condenser means to said evaporator means, and means responsive to the temperature of the air leaving said evaporator means for by-passing refrigerant from a point ahead of said flow control means to a point beyond said evaporator means in response to a decrease in the temperature of the air leaving said evaporator means.
